SUPPORTING AND ACTUATING MEANS FOR
VERTICALLY RECIPROCATING MEMBERSCarlo Schleifer, Milan, Italy; vested in the Alien
Property CustodianApplication February 20, 1940, Serial No. 319,977
In Italy February 22, 1939

7 Claims. (Cl. 242—43.3)

In existing machines for spinning, twisting, winding-on and doubling, there are movable members actuated with a vertical reciprocating movement. The carriage that carries the spindles in fly frames, the spindle carriage or ring rail in continuous spinning or twisting ring frames, and the ring rail that carries the thread guides or bells in certain special spinning machines, are members of this nature.

In the constructions hitherto known, these movable members are supported, guided and actuated by the aid of vertical rods or pokers sliding in the sleeves or couplings substantially integral with the frame of the machine, and actuated through the medium of suitable transmission members by a rod extending in the longitudinal direction of the machine and actuated with a reciprocating motion by the winding-on eccentric or other equivalent kinematic drive.

This arrangement exhibits various disadvantages. Above all in machines of considerable length, such as spinning machines, it is difficult to ensure and maintain correct parallelism between the guiding rods, and it is also difficult to effect the lubrication thereof for the purpose of ensuring smooth sliding in the interior of the coupling sleeves in which the said rods slide with accurate adjustment. There are consequently considerable losses by friction, and a great expenditure of motive power. Furthermore, owing to the fact that the movable member is positively driven only during its ascent, whereas its descent is accomplished under the action of gravity, this member cannot be accurately balanced for the purpose of reducing the expenditure of motive power.

Now the present invention, the object of which is to obviate the aforementioned disadvantages, relates to a device for supporting and actuating the said movable members, according to which each member is not supported and actuated by rigid rods, but is on the contrary suspended by the aid of flexible members from driving members having an oscillating rotary movement, with which the said flexible members are positively engaged, and in relation to which they unwind now in one direction and now in the opposite direction, so that the movable member suspended therefrom executes a vertical ascending and descending movement.

These flexible members may be continuous, that is to say, in the form of a closed ring, unwinding also in engagement with tensioning members, so as to ensure the actuating of the movable mem-

ber both during its ascent and during its descent, thereby enabling the weight to be accurately balanced.

According to a further feature of the present invention the movable members are subdivided into a plurality of short elements which elements are separately actuated in a manner similar to that in the form of the invention in which the longer movable members are employed. In this way the disadvantages arising from any lack of parallelism between the vertical guiding members and the totality of the movable members is reduced to a minimum.

Some forms of construction of the invention are diagrammatically illustrated merely by way of example in the accompanying drawings, in which:

Figures 1 and 2 show in side elevation and in transverse section respectively the drive for the spindle carriage of a spinning or twisting machine;

Figure 3 is a view similar to Figure 2 showing a modification;

Fig. 3A is a perspective view of certain portions of Fig. 3;

Figure 4 shows an end view of a device for superposing upon the alternating movement of the spindle carriage an intermittent slow vertical movement which is always in the same direction;

Figures 5 and 6 show two forms of windings that may be produced with this spindle carriage drive;

Figures 7 and 8 show on a larger scale two forms of flexible suspension members for the movable member, and the drive associated therewith;

Figure 9 shows in side elevation a modification in the drive of the spindle carriage; and

Figures 10 and 11 show in side elevation and in transverse section respectively another modification.

According to the embodiment illustrated in Figures 1 and 2, each of the spindle carriages of the two halves *a* and *a'* that constitute the continuous spinning or twisting frame is subdivided into a plurality of bolster rail elements *1* and *1'* of limited length. Each of these rails, carrying the spindles *2* and *2'*, is so guided as to be capable of sliding in a vertical direction by the aid of sleeves or couplings *3* and *3'* along the guide rods *4* and *4'* respectively, which are substantially integral with the frame *5* of the machine. Each of the rails *1* and *1'* is suspended

by the aid of an endless flexible member 6 or 6'. The rails 1 and 1' are anchored at 6° and 6° to endless members 6 and 6' respectively, said endless members being in positive engagement with driving wheels 7 and 7', keyed to transverse shafts 8, rotatably supported by fixed bearing brackets 9 substantially integral with the frame 5. These flexible members also positively engage tensioning wheels 10 and 10', keyed to transverse shafts 11, which are also rotatably supported by the frame 5.

The flexible suspension members may consist of chains, as shown in Figure 7, and in this case the wheels 7 and 7' are ordinary toothed wheels with which the chains mesh; or alternatively a flange wheel 70 may be employed to which a cable or a metallic tape 60 is anchored as at 12 to the periphery of the wheel (Fig. 8).

For the actuating of the various elements of the spindle carriage a rod 13 is provided, which is so guided as to be capable of sliding in the longitudinal direction of the machine, and is reciprocated by a cam or other equivalent member. In the example illustrated, this cam member comprises a cylinder 14 having cam groove 14' therein. A roller 15 is secured to rod 13 and engages the groove. The rod 13 is provided at suitable points with screw threaded portions or worms 13', which mesh with worm wheels 16, keyed to the shafts 8. During the reciprocating movement of the rod 13 these worms 13' also function as racks and thereby impart an oscillating rotary movement to the shafts 8 and to the wheels 7 and 7', which movement is converted into an alternating vertical movement through the medium of the flexible members 6 and 6', said flexible members being positively controlled both during the ascent and during the descent of the elements 1 and 1' of the spindle carriage.

With a view to reducing the force required for the raising of the elements 1 and 1' of the carriage, these elements may be accurately balanced by the aid of counterpoises 17, acting through the medium of flexible members 18 upon pulleys 19 keyed to the shafts 11. Alternatively, the weight of the elements 1 may be directly balanced with the weight of the elements 1' on the other half of the machine, through the medium of the same flexible suspension members 6 and 6' by connecting the rails to the flexible members in such a manner that one rail will ascend while the other descends, as diagrammatically indicated in the modification illustrated in Figs. 3 and 3A.

With the simple vertical alternating movement impressed upon the elements 1 and 1' of the spindle carriage, cylindrical bobbins, such as the bobbin 20 of Fig. 6, may be obtained, having a height h equal to the amplitude of the alternating movement impressed upon the said elements. It is also possible to obtain bobbins with a conical point, such as the bobbin 21 of Fig. 5, if there is impressed upon the longitudinal rod 13 a rotary as well as an axially reciprocable movement. The last named axially reciprocable movement of rod 13 will produce a vertical alternating movement of amplitude h' equal to the height of the winding traverse, and at the same time the intermittent unidirectional rotary motion of the rod 13 will gradually lower the spindle relative to the winding point over a total distance H during the entire winding of the package. The screw threaded portions 13', by also functioning as screws or worms, will therefore impress upon

the worm wheels 16 an intermittent rotary motion, so that upon the alternating movement of amplitude h' of the elements 1 and 1' there will be superposed an intermittent progressive raising or lowering movement of amplitude H , which will determine the formation of the bobbin 21 of Figure 5.

In order to impress upon the rod 13 an intermittent rotary movement, recourse may be had for example to the device shown in Figure 1, and in detail on a larger scale in Figure 4. According to this device, there is made substantially integral with the cam cylinder 14 a heart-shaped cam 22, designed to actuate, with a reciprocating motion, a push rod 23, which, owing to the fact that it is jointed to one of the arms of a bent lever 24 oscillatably mounted upon a shaft 25, causes this lever to oscillate. The other arm of the lever 24 is provided with a pawl 26, engaging with a ratchet wheel 27, which is substantially integral with a wheel 28, which, by the aid of a chain 29, transmits the motion to another wheel 30, which wheel is keyed by means of a sliding key 31 to the end of the rod 13. At each revolution of the cam cylinder 14 there is impressed upon the rod 13 a small intermittent rotary movement, so that upon the alternating vertical movement of the elements 1 and 1' of the carriage there is superimposed a slow descending movement, in such a manner as to obtain the bobbin 21 shown in Figure 5. If, instead of the spindle carriage, reciprocable ring rails are mounted upon the flexible members, the rotating spindles will remain in a relatively stationary position and therefore the said slow movement H would have to be an ascending movement, which would be obtained by impressing a reverse rotation upon the rod 13, or else by making use of an inverse pitch for the screw 13'.

The flexible members 116 that support the elements 1 of the carriage may equally well be discontinuous, as shown in Fig. 9. In this case, the said flexible members, still engaging with the actuating wheels 7, keyed on to the shafts 8, which wheels are actuated with an oscillating rotary motion, are anchored at one end, at 6° to the element 1 of the carriage while at the other end of the flexible members a force F is provided, said force comprising a counterpoise with a view of balancing the weight of the element 1 of the carriage. Alternatively, the weight of the elements 1 may be balanced directly against the weight of the elements 1' on the other half of the machine through the medium of flexible suspension members 61 and 61', by vertically staggering the points of attachment 6°, 6°, one with the other on opposite sides of the machine in such a manner that when element 1 rises the other element 1' descends, and conversely, as indicated diagrammatically in Figures 10 and 11.

When discontinuous flexible elements are employed, as in the examples illustrated in Figures 9, 10 and 11, the positive actuation of the elements 1 and 1' of the carriage takes place only during the ascent, whereas the descent is effected under the action of gravity.

In the device for supporting and actuating the movable members hereinbefore described, owing to the suspension and the actuation of these movable members by the aid of flexible members, and furthermore owing to the subdivision of these movable members into a plurality of short elements, the friction along the guiding members 4 and 4' is reduced to a minimum, either owing to the fact that accurate ad-

justment of the guiding sleeves 3 and 3' is no longer required, or else owing to the fact that any defects of parallelism between the guiding members of the various elements have no influence. The expenditure of motive power for the actuation of the machine is thus considerably reduced, while all the disadvantages presented by the actuating devices hitherto known are eliminated.

Although the invention has been described in its application to the actuation of the spindle carriage of a ring spinning frame or ring doubler, it is obvious that with appropriate modifications, and without going outside the scope of the invention, it is equally applicable to the actuation of the ring rail of these same spinning or twisting machines, or to the bell-carrying rail or thread guide rail in certain special spinning machines, and in general to any movable member of spinning, twisting, winding-on and like machines.

What I claim is:

1. A supporting and actuating device for spinning machines, twisting machines, winding machines and the like comprising, an actuating shaft having a rotary oscillating motion, a pair of actuating elements secured to said actuating shaft, a tensioning countershaft journalled parallel to and vertically above the actuating shaft, a pair of circular return guiding elements secured to said tensioning countershaft, a pair of continuous flexible members movable about said countershaft in the same direction, each of said flexible members passing round and positively engaging an actuating element and also passing round and positively engaging a circular return guiding element thereby providing an ascending section and a descending section in the flexible member, a pair of vertically reciprocable traverse members, means for separately securing one of said traverse members to the ascending section of one flexible member, and means for separately securing the other of said traverse members to the descending section of the other flexible member, whereby one traverse member will ascend while the other descends.

2. In a builder motion for spinning machines, twisting machines, winding machines and the like comprising, a first shaft having a rotary oscillating motion, a countershaft journalled parallel to and vertically above said actuating shaft, guiding means secured to said countershaft, continuous flexible driving means surrounding said guiding means and movable back and forth by said oscillating first shaft, thereby providing an ascending section and a descending section in the flexible driving means, a pair of traverse members, means for securing one of said traverse members to the ascending section of the flexible driving means, and means for separately securing the other of said traverse members to the descending section of the flexible driving means, whereby one traverse member will ascend while the other descends.

3. In a builder motion for spinning machines, twisting machines, winding machines and the like comprising, a first shaft having a rotary oscillating motion, a countershaft, guiding means secured to said countershaft, flexible driving means

encircling said guiding means and positively movable back and forth by said oscillating first shaft, thereby providing oppositely movable sections in the flexible driving means, a pair of traverse members, means for securing one of said traverse members to one of said sections, and means for securing the other traverse member to the other of said sections, whereby one traverse member will move in a direction opposite to the direction of movement of the other member.

4. In a builder motion for spinning machines, twisting machines, winding machines and the like comprising, a first shaft having a rotary oscillating motion, a countershaft, guiding means secured to said countershaft, flexible driving means encircling said guiding means and positively movable back and forth by said oscillating first shaft, thereby providing oppositely movable sections in the flexible driving means, a pair of traverse members, means for securing one of said traverse members to one of said sections, means for securing the other traverse member to the other of said sections, whereby one traverse member will move in a direction opposite to the direction of movement of the other member, a worm gear fixedly secured upon said first shaft, a worm shaft, a worm fixed upon said worm shaft and meshing with said worm gear, means for axially reciprocating said worm shaft and worm to impart reciprocating movement to said traverse members, and means for intermittently rotating said worm shaft and worm in the same direction, whereby a slow unidirectional displacement will be superimposed upon the reciprocating movement of the traverse members.

5. A builder motion according to claim 2 including a worm gear fixedly mounted on one of said shafts, a worm shaft, a worm fixed upon said worm shaft and meshing with said worm gear, means for axially reciprocating said worm shaft and worm to impart reciprocating movement to said traverse members, and means for intermittently and unidirectionally rotating said worm shaft and attached worm whereby a unidirectional displacement will be superimposed upon the reciprocating movement of the traverse members.

6. In a builder motion for spinning machines, twisting machines, winding machines and the like comprising a pair of traverse members, endless flexible means, means for supporting said flexible means for back and forth movement about two spaced points enclosed by the flexible means thereby providing oppositely movable sections in the flexible means, means for securing one traverse member to one of said sections, and means for securing the other traverse member to the other of said sections.

7. A builder motion according to claim 6 including a transmission device for superimposing a unidirectional displacement upon the back and forth movement of said traverse bars, said device comprising a worm wheel operatively connected to said flexible member, a worm meshing with said gear, means for axially reciprocating said worm, and means for unidirectionally rotating said worm.

CARLO SCHLEIFER.
